COUNTING-DEVICE FOR COMPUTING-MACHINES.

1,128,973.

Specification of Letters Patent. Patented Feb. 16, 1915.

Application filed December 8, 1914. Serial No. 876,179.

To all whom it may concern:

Be it known that I, JOHN EMIL WILLIAM GREVE, subject of the Emperor of Germany, residing at Chemnitz, Saxony, Germany, have invented certain new and useful Improvements in Counting Devices for Computing-Machines, of which the following is a specification.

This invention relates to computing machines, and has particular reference to improvements in the action of the counting-devices.

It is the object of the present invention to provide a mechanism which is brought into operation when a total or sub-total is being taken, to lock the tens-transfer lever positively in its normal position.

In computing machines, whose computing mechanism is brought into and out of engagement with the setting gears by a translating action, it is well known, either to hold the counting mechanism normally out of engagement with the setting devices or to have it in constant engagement therewith. Such computing machines can also be provided with a counting mechanism, which is changeable for the purposes of addition and subtraction.

The tens transfer levers in the mechanisms which have been known heretofore frequently do not constitute a positive stop of the necessary dependable character for the transfer-pins of the counting wheels, during the taking of totals and sub-totals, (when said wheels or disks are returned to zero positions), but, as a result of the momentum of the approaching transfer pins during the rapid action of the machine, are released. In order to remedy this evil, a mechanism is provided, according to this invention which positively sets a locking device for the tens-transfer lever, in order to assure its retention in its normal position, said locking device being controlled by the totalizing lever.

One example of the subject matter of the present invention is shown in the accompanying drawing, in which the figure shows an elevation, partly in section of the mechanism, all well-known parts of the machine and those not necessary to the present showing being omitted for the sake of clearness.

The counting disks 1 and 2, which, according to the present form of the inven-

tion, are constantly engaged in pairs, possess the tens-transfer pins 1^a and 2^a. The counting disks 2 are also provided with numeral disks (not shown). Said counting disks are contained in a housing, which for the purpose of shifting from a position for addition to one of subtraction or vice versa, is pivoted for oscillatory movement on a shaft or axis 3. In normal position, the counting wheels are found in constant engagement with the toothed setting gears or sectors 4, which are slidably mounted on the carrier arms 5. Said gears or sectors 4 are moved the width of a tooth, when the tens-transfer means is brought into action. Upon the shaft 7 is mounted the two-armed oscillatory tens-transfer lever 6, having the projections 8. Said projections 8 are provided with cam-faces 9, which are adapted to co-operate with the transfer-pins 1^a and 2^a. Said tens-transfer lever operates in a well-known manner simultaneously with the shifting elements 10 and 11 which operate to position the setting gears 4 the distance equal to the width of a tooth, said elements 10 and 11 being actuated by a spring 12, and are returned to the normal position indicated in the drawing by means of a mechanism which is not shown. Since the manner of operation of the elements is well known and does not form a part of the present invention, it is believed that a further showing or description thereof is unnecessary.

Should the counting devices happen to lie in such a position that the transfer pins 1^a of the counting disk 1 rests on the cam-face 9 of the transfer lever 6, and should it be desired at this time to shift from the position of addition to subtraction, by swinging the counting mechanism about the axis 3, then it would occur that the pin 1^a would push the transfer-lever 6 toward the left, or else jam the mechanism, unless the cam-face 9 was so formed that its operative surface was an arc of a circle whose center was the axis 3. In this latter case, however, the cam-face would become an inoperative element, permitting the pin 1^a to merely ride thereover. Again, if, for example, the position of the counting-wheels is taken, as indicated in the drawings, then, when a total or sub-total is taken, the pin 1^a would strike with comparatively heavy force against the cam-face 9 of the lug 8, 110

and tend to throw the transfer-lever 6 to the left, in case no means is provided to lock said lever 6 against this tendency.

In order to secure the tens-transfer lever 5 in its normal position during the taking of totals and sub-totals, a lock-lever 14 having a lug or projection 14' is provided, said lever 14 being fixed on an oscillatory shaft 13 so that the projection 14' can be moved 10 into and out of engagement with a recess or notch 6' in the upper end of the transfer lever 6. Upon the shaft 13 is also fixed an arm or lever 15, which is connected to the totalizing lever (not shown) by means of a 15 connecting rod 16; said lock-lever 14 being thereby actuated to engage or release the transfer-lever 6.

The operation of the described mechanism is as follows:—When the totalizing lever is 20 actuated to draw a total, the draw-bar 16 is drawn down thereby out of the dotted line position of the drawings, into locking engagement with the recess 6', as shown in full lines, whereby the lever 6 is prevented

from being swung to the left by any action 25 other than a proper one. When the totalizing lever is in its normal position, the lever 14 is maintained in elevation so as to be free from the notch or recess 6' and the lever 6 is free to move to any operative im- 30 pulse impartial thereto.

What I claim as my invention is:—

In a counting mechanism for computing machines, the combination with counting wheels mounted for oscillation into its adding and 35 subtracting positions, means for setting up the counting wheels, a tens-transfer lever, transfer pins carried by said counting wheels to coöperate with said transfer lever, and a locking lever to engage said transfer lever when the counting mechanism is operated to take a total or a sub-total.

In testimony whereof I affix my signature in presence of two witnesses.

JOHN EMIL WILLIAM GREVE.
